UNITED STATES PATENT OFFICE.

MICHAEL W. NEUENS, OF PORT WASHINGTON, WISCONSIN, ASSIGNOR TO
WESTERN IMPLEMENT COMPANY, OF PORT WASHINGTON, WISCONSIN.

GRINDING-MACHINE.

SPECIFICATION forming part of Letters Patent No. 703,212, dated June 24, 1902.

Application filed December 30, 1901. Serial No. 87,761. (No model.)

To all whom it may concern:

Be it known that I, MICHAEL W. NEUENS, a citizen of the United States, and a resident of Port Washington, in the county of Ozaukee and State of Wisconsin, have invented 5 certain new and useful Improvements in Grinding-Machines; and I do hereby declare that the following is a full, clear, and exact description thereof.

10 My invention has for its object to simplify and cheapen grinding-machines of that class especially designed for agriculturists; and it consists in certain peculiarities of construction and combination of parts hereinafter 15 particularly set forth with reference to the accompanying drawings and subsequently claimed.

Figure 1 of the drawings represents a gear side elevation of a grinding-machine in accordance with my invention, parts of the same being broken away and in section; Fig. 2, a plan view of the machine, partly in horizontal section; Fig. 3, a vertical longitudinal section of said machine, indicated by lines 3 3 25 in the second and fourth figures; Fig. 4, a horizontal section of the aforesaid machine, indicated by lines 4 4 in the third figure; and Fig. 5, a partly-sectional front elevation of clamp and tension mechanism embodied in 30 the machine.

Referring by letter to the drawings, A indicates the base of my machine, provided with lateral end ears having apertures for screws b, by which said base is made fast to 35 a board B or other suitable support. Fitting a longitudinal recess in the forward portion of base A is the shank c of a bracket C, and a bolt d, engaging a longitudinal slot of said base and an aperture provided in the bracket- 40 shank, has a set-nut e run thereon to hold said bracket in adjusted position.

Mounted in bearings constituting arms of bracket C is a pivot-rod f of a pair of clamp-jaws D D', both of which are engaged by a 45 bolt g, having a set-nut h run thereon. A screw E is adjustable in a lug i of clamp-jaw D against an arm j of bracket C to regulate tension of a spiral spring F, hooked at its

ends to clamp-jaw D' and the bolt d aforesaid. A similar spring k is arranged under compression between the head of the tension-screw and clamp-jaw D to prevent automatic play of said screw incidental to jarring of the machine.

In match fit with the high rear portion of a 55 longitudinal web m of base A is a standard A', having a foot n extending under said base, and a bolt p, engaging the base-web and the standard, has a set-nut q run thereon. The head of the standard is in the form of a 60 sleeve r, and by means of a set-screw s an arbor G is made fast in engagement with the sleeve. Astraddle of the sleeve end of the standard A' is the yoke end of an arm H in oscillative engagement with arbor G, said 65 standard being provided with a lug t, that constitutes a rest for said arm and limits downward play of same. Fitting a longitudinal recess in the forward portion of arm H is the shank u of a hanger I for the arbor J of 70 a grinding device K, and a bolt w, engaging a longitudinal slot in said arm and an aperture in the hanger-shank, has a set-nut v run thereon to hold said hanger in adjusted position. The grinding device herein shown is 75 one especially designed for sharpening triangular knife-sections of sickle-bars, and a portion of such a bar, with knife-sections thereon, is shown held in the clamp above specified.

Held to turn loose on arbor G is a driving spur-wheel L, that meshes with a pinion M, constituting part of the hub of another spur-wheel N, arranged to turn on a lateral boss x 85 of arm H and mesh with a pinion O, fast on arbor J of the grinding device. The hub of spur-wheel L is partly in the form of an eccentric P, engageable with a rocker Q in the form of a link, one end of which is held in pivotal connection with a rear branch A" of 90 the machine-standard, the other end being in the form of a fork engaging an annular shoulder of boss x aforesaid. The standard branch A" is shown provided with a segmental slot engaged by a shouldered bolt y, that constitutes the pivot for rocker Q, and a set-nut z 95

8c

is run on the bolt to clamp the same in adjusted position in said slot. Spur-wheel L is shown provided with a radial side recess and slot. A crank R has an offset b' engaging the 5 wheel-recess, and a bolt c' engages the crank-offset, wheel-recess, and a set-nut d', this nut being tightened on the bolt to hold the crank in adjusted position, adjustment of said crank serving to vary leverage on said wheel.

10 A sickle-bar is clamped in the machine to have the knives thereof face the grinding device K, bracket C, hanger I, and tension of spring F being properly adjusted. By turning crank R rotatory motion is imparted to 15 the grinding device simultaneous with an oscillation of the same due to the action of eccentric P in rocker Q, high speed being had with but little effort on the part of the operator in proportion to set of crank R in connection 20 with the driving spur-wheel, and adjustment of hanger I compensates for wear of said grinding device and knife-sections on which it operates.

Having thus described my invention, what 25 I claim as new, and desire to secure by Letters Patent, is—

1. A grinding-machine comprising a base and standard, an arm in swing connection with the standard, a rotatory grinding device 30 in suspension from the arm, a sickle-bar clamp in pivotal connection with the base, a clamp-controlling spring, means for regulating spring tension, grinding-device drive-gear having the main wheel thereof provided with 35 an eccentric, and a rocker astride the eccentric in connection at its ends with said arm and a branch of said standard.

2. A grinding-machine comprising a standard having the upper end thereof in the form 40 of a sleeve, an arbor held fast in the sleeve, an arm having a yoke end astraddle of said sleeve and loose on the arbor, a rotatory grinding device in suspension from the arm, a sickle-bar clamp in pivotal connection with 45 the base, a clamp-controlling spring, means for regulating spring tension, grinding-device drive-gear having the main wheel-hub thereof in the form of an eccentric loose on said arbor, and a rocker astride the eccentric in 50 connection at its ends with said arm and a branch of said standard.

3. A grinding-machine comprising a base and standard, an arm in swing connection with the standard, a rotatory grinding device 55 in suspension from the arm, a pivotal sickle-bar clamp having a bracket-shank thereof adjustable on the base longitudinally of the same, a clamp-controlling spring, means for regulating spring tension, grinding-device drive-gear having the main wheel thereof provided with an eccentric, and a rocker astride the eccentric in connection at its ends with 60 said arm and a branch of said standard.

4. A grinding-machine comprising a base

and standard, an arm in swing connection 65 with the standard, a rotatory grinding device having a hanger provided with a shank in adjustable connection with the arm longitudinally of the same, a sickle-bar clamp in pivotal connection with the base, a clamp-controlling spring, means for regulating 70 spring tension, grinding-device drive-gear having the main wheel thereof provided with an eccentric, and a rocker astride the eccentric in connection at its ends with said arm 75 and a branch of said standard.

5. A grinding-machine comprising a base and standard, an arm in swing connection with the standard, a rotatory grinding device 80 in suspension from the arm, a sickle-bar clamp 80 consisting of a base-bracket, a pivot-rod supported by the bracket, clamp-jaws loose on the rod, a spiral spring connecting one of the jaws with a stationary portion of the machine, a tension-screw carried by the other of the 85 jaws to abut an arm of said bracket, a bolt engaging both jaws and a set-nut on the bolt; grinding-device drive-gear having the main wheel thereof provided with an eccentric, and a rocker astride the eccentric in connection 90 at its ends with said arm and a branch of said standard.

6. A grinding-machine comprising a base and standard, an arm in swing connection with the standard, a rotatory grinding device 95 in suspension from the arm, a sickle-bar clamp in pivotal connection with the base, a clamp-controlling spring, means for regulating spring tension, a spur-wheel having a pinion-hub loose on a lateral boss of said arm, a pinion on the grinding-device arbor in mesh with 100 said spur-wheel, an eccentric hub-driving spur-wheel loose on an arbor constituting the swing-arm axis, and a rocker astride the eccentric hub in connection at its ends with 105 said swing-arm boss and a branch of said standard.

7. A grinding-machine comprising a base and standard, an arm in swing connection with the standard, a lug on said standard 110 arranged to constitute a rest for the swing-arm, a rotatory grinding device in suspension from said arm, a sickle-bar clamp in pivotal connection with the base, a clamp-controlling spring, means for regulating spring tension, grinding-device drive-gear having the main wheel thereof provided with an eccentric, and a rocker astride the eccentric in connection 115 at its ends with said arm and a branch of said standard.

8. A grinding-machine comprising a base and standard, an arm in swing connection with the standard, a rotatory grinding device in suspension from the arm, a sickle-bar clamp in pivotal connection with the base, a clamp-controlling spring, a screw arranged 120 to regulate tension of said spring, a spiral spring on the screw between its head and the

adjacent clamp-jaw, grinding-device drive-gear having the main wheel thereof provided with an eccentric, and a rocker astride the eccentric in connection at its ends with said

5 arm and a branch of said standard.

In testimony that I claim the foregoing I have hereunto set my hand, at Port Washingt-

ton, in the county of Ozaukee and State of Wisconsin, in the presence of two witnesses.

MICHAEL W. NEUENS.
